UNITED STATES PATENT OFFICE.

WILLIAM HENRY HASKINS, OF SAN JOSE, CALIFORNIA.

ROLLER WINDOW-SCREEN.

1,132,773.

Specification of Letters Patent. Patented Mar. 23, 1915.

Application filed July 15, 1913. Serial No. 779,127.

To all whom it may concern:

Be it known that I, WILLIAM HENRY HASKINS, a citizen of the United States, residing at San Jose, in the county of Santa Clara and State of California, have invented certain new and useful Improvements in Roller Window-Screens, of which the following is a specification.

My invention relates to improvements in roller window screens, and consists of a device whereby screens may be attached to rollers and to each window sash, and automatically wound and unwound as the sashes are raised or lowered. This screen, and the devices operating it, are so constructed and arranged as to keep flies, insects, and small flying particles of any kind from getting into the room, and said devices are so arranged that when the windows are closed said screens are wound up and out of sight. The devices are so constructed that the screens and rollers may be removed at any time to be repaired or replaced, the inside apron or upper casing as the case may be, being put on with screws.

One object of my invention is to provide a window screen having a roller and a spring to operate said roller with said screen that shall be both elastic and durable and of sufficient capacity to do the work easily, the same being in proportion to the size of the screen to be controlled.

Another object of my invention is to provide a window screen that shall necessitate the fewest possible changes in the construction and appearance of the window itself either in the frame or sash.

Another object of my invention is to provide a rolling window screen so simple in construction as to be of comparatively small cost, and one in which all parts are so well adjusted as to minimize the friction and render said screen substantial, durable, and practical.

Other objects of this invention will be apparent as it is more fully set forth.

My invention consists in the construction and combination of its various parts, substantially as will be hereinafter fully described and specifically set forth in the claims.

In the accompanying drawings,—Figure 1 is a perspective view of a window with my screen attached, parts being broken away. Fig. 2 is a front elevation of the roller and spring with the screen removed.

Fig. 3 is a vertical section through the screen at point A, parts being broken away. Fig. 4 is a vertical section through the window and screen at point B Fig. 1, parts being broken away. Fig. 5 is a section through the screen and sash at point C Fig. 1, parts being broken away. Fig. 6 is a section through the screen and sash at point D Fig. 1, parts being broken away. Fig. 7 is a perspective view of one of the roller holders and the spring attachment in position. Fig. 8 is a perspective view of the other roller holder in position. Fig. 9 is a perspective view of the locking pin 22 of Fig. 8.

Reference being had to the accompanying drawings, and to letters and figures of reference marked thereon, which form a part of this specification, 1 represents a window frame to which my improved window screen is attached, said screen having a metal binding at each end thereof shown at 1^a and 1^b respectively. 2 is a lower sash to which is attached said screen at points A, C, D.

3 is a wire screen passing down and behind the window stool 4 and through the longitudinal opening in the sill of window frame at 5 and connecting to roller 6 by fastenings shown at 7 and groove 7^a. Said fastenings may be screws or any other suitable mode of fastening said screen 3 to roller 6 in connection with said groove 7^a. Said roller 6 may be made of wood or any other suitable material having a center shaft as shown at 8 and 8^a, one end of said roller 90 being turned down and back a distance from the end thereof, as shown at 9, for the purpose of receiving coiled spring 10, said spring being closely wound and when released the size of the main portion of said roller 6 and passed over the turned down portion 9 of said roller 6 and fastened to said roller at inner end as shown at 11. The outer end of said spring 10 is hook-shaped as shown at 12. When the 100 roller and spring are in place below the window frame this hook is connected to fastening shown at 13. Said spring is closely wound because each coil represents a certain amount of capacity, the object being to secure the greatest amount of capacity disposed within the smallest space. It is slightly open when the outer end is connected with hook 13, just sufficient to allow for expansion lengthwise.

Holder 14 is made of iron or any other suitable material dishing in shape to re-

ceive the end of reduced portion of roller 6, having a hole bored through the center thereof, as shown at 15, for the purpose of a bearing for center shaft 8. Said holder 14 is fastened to the stud extending below to which is nailed the side casing of window frame; or other means provided for that purpose, by fastening shown at 16. On one side of said holder is cut out a segment shown at 17, for the purpose of allowing fastening 13 to be placed within the circumference of said holder 14 as shown in Fig. 7 after the same is fastened in its place. This together with circular form and size of holders permits end of screen to revolve around holders if space for locating roller is limited to the same distance in length as width of window.

Holder 18 is made of iron or any other suitable material of the proper thickness, 20 circular in shape and of the proper size having a hole bored through the center thereof, shown at 19, for the purpose of a bearing into which is inserted center shaft 8^a. Said holder 18 having a slot 20 cut through from 25 its outer circumference to and in connection with shaft bearing 19, the same being dovetailed in shape to receive and retain means for holding shaft 8^a in bearing 19. This slot 20 is for the purpose of inserting shaft 8^a 30 into its bearing 19 after said holder 18 has been fastened in its proper place by fastening shown at 21. Into this slot 20 is inserted a stop 22 preferably of metal, for the purpose of retaining said shaft 8^a in place in 35 bearing 19 after the same has been inserted therein, said stop being fastened in place by small screw or nail as shown at 23, the inner end of said stop being bent at a right angle to the main portion thereof as shown 40 at 24, the same being in shape to correspond with slot 20.

Lower sash 2 has a rabbet cut along the lower edge thereof shown at 25 for the purpose of receiving metal binding 1^a, fastened 45 to end of screen 3, there being disposed in said binding two or more holes 32 and one or more screw bolts 27 according to width of window. At point A in said sash is a recess 26 cut back a distance to receive nut on 50 said screw bolt 27, thus forming one of the supports for said screen, said bolt also serves to prevent said screen from being drawn down below the window sill when the same is detached from the sash, and also fastens 55 cord 28 to screen binding. This cord is for the purpose of handling said screen 3 when the same is detached from the sash, and when not in use it is tucked between the binding and the shoulder to the rabbet, or if 60 screen is detached between binding and window stool. At point C are turnable hooks 29 which are for the purpose of holding said screen snugly in position against said sash when turned down or releasing the same 65 when turned upwardly as shown in dotted

lines at 30, said hooks being screwed in straight and bent over after they are in place. At points D are pins driven into said sash as shown at 31. These pins are for the purpose of affording additional supports to said screen when the same is placed in position through corresponding holes 32 in said binding 1^a.

This roller screen is equally as practical when located above the lintel in said frame 75 1, the screen working through a longitudinal opening in said lintel and all of these same means may be attached to the upper sash within a rabbet in upper rail thereof and the same operated in the same manner 80 as the lower sash.

My device is adjusted and operated as follows:—The screen is tightly rolled on roller 6 and firmly tied. The end of spring 10 is drawn out endwise from end of screen 85 and hook 12 placed on hook or pin 13. Shaft pin 8 is placed in bearing 15, and shaft pin 8^a placed in bearing 19 through slot 20. Stop or key 22 is inserted in said slot 20 and fastened securely in position by 90 fastening means 23. The roller is then revolved a sufficient number of times to give the spring 10 the proper tension, the strings are cut, and the upper part of screen 3 and its binding 1^a is then passed upwardly 95 through slot 5 in the window sill. The cord 28 and the bolt and nut 27 are then securely fastened in position as shown in Fig. 3. Holding the screen by cord 28, nut 27 is inserted into recess 26, holes 32 in binding 1^a 100 engaging pins 31 at points D. Hooks 29 are then turned downwardly into position and cord 28 tucked into the rabbet in sash 2 and above binding 1^a. The screen 3 will now automatically follow sash 2 whenever the same is raised or lowered. It is pointed out that the bolt and nut 27 perform a treble function; 1st, they afford a fastening for cord 28; 2nd, they assist in supporting screen 3 when they are inserted in hole 26; 3rd, they prevent the binding 1^a from passing downward through slot 5 in window frame 1 when screen 3 is detached from sash 2. While this screen has been described as being fitted to a lower sash, it may be adjusted to an upper sash and operated in the same way.

Having thus described my invention and the operation of the same, what I claim as new and desire to secure by Letters Patent is,—

1. In a rolling window screen the combination of a roller having one end portion thereof reduced in diameter with an actuating spring disposed thereon and an axle rod member secured in each end thereof, and a holder for said screen roller having a recess formed therein adapted to receive said diminished end portion of said roller, and having countersunk notches formed in the edge thereof and a segment removed from 115 120 125 130 135 140 145 150 155 160 165 170 175 180

one side thereof, and means independent of said holder located within the space of said removed segment adapted to engage and hold one end of said spring as shown and described.

2. In a rolling window screen the combination of a roller having one end portion thereof reduced in diameter with an actuating spring disposed thereon and 10 an axle rod member secured in each end thereof, and a holder for said roller having a slot cut through the body thereof extending from the center to the outer

edge thereof and being of greater width on one face thereof than on the other, 15 and a metallic key bent and formed in such a manner as to fit into said slot when said holder is in position, and adapted to be retained therein, substantially as shown and described.

In testimony whereof I affix my signature in the presence of two witnesses.

WILLIAM HENRY HASKINS.
